UNITED STATES PATENT OFFICE.

SOLOMON EUGENE HALL, OF HONEOYE FALLS, NEW YORK, ASSIGNOR OF
ONE-HALF TO GEORGE HILL, OF SAME PLACE.

WRENCH.

SPECIFICATION forming part of Letters Patent No. 466,564, dated January 5, 1892.

Application filed October 14, 1891. Serial No. 408,656. (No model.)

To all whom it may concern:

Be it known that I, SOLOMON EUGENE HALL, of Honeoye Falls, in the county of Monroe, in the State of New York, have invented new and useful Improvements in Wrenches, of which the following, taken in connection with the accompanying drawings, is a full, clear, and exact description.

My invention relates to improvements in wrenches, and has for its object the production of a simple and effective device which is strong, durable, easily adjusted, and very efficient in use.

To this end the invention consists, essentially, in a handle having an annular guide-groove, a disk provided with a shoulder adapted to engage said groove, a guideway extending transversely of the disk, jaws movable in said guideway and provided with a recess in 20 their sides for engaging a projecting shoulder of the way, an adjusting-screw for moving the jaws toward and away from each other, and a dog for securely locking said disk and handle together.

The invention furthermore consists in a pair of dogs having a portion of their face ratchet-shaped, a sliding block or cam for engaging the dogs and throwing them alternately into and out of operation, a shoulder provided 30 upon one or both of said dogs, whereby it may be partially revolved in order that the dog may engage the disk positively when the handle is rocked in either direction; and it still furthermore consists in the detail construction 35 and arrangement of the parts, all as hereinafter more particularly described, and pointed out in the claims.

In describing this invention reference is had to the accompanying drawings, forming 40 a part of this specification, in which like letters indicate corresponding parts in all the views.

Figure 1 represents a front face view of my improved wrench, the greater portion of the handle being broken away. Fig. 2 is a longitudinal vertical sectional view of the parts as illustrated in Fig. 1. Fig. 3 is a rear view of the wrench as illustrated in Fig. 1, the handle being removed for the purpose of illustrating 45 the underlying parts. Fig. 4 is a transverse vertical sectional view taken on line *yy*, Fig.

1. Fig. 5 is a rear face view of the movable block or cam for forcing the ratchet-dogs into and out of operative position. Figs. 6 and 7 are respectively isometric perspectives of the 55 ring on the handle and a hub removably secured thereto. Fig. 8 is an isometric perspective of the wrench-jaw; and Fig. 9, a detached view of the ratchet-dogs in position for firmly securing the revoluble disk or rod 60 upon which the jaws are mounted to the handle, irrespective of the movement of the handle, when it is not desired to utilize the same as a ratchet-wrench.

The handle A may be of any desirable form, 65 size, and construction, being preferably formed at one extremity with a ring *a*.

B represents a hub or plate which forms part of the handle and is secured thereto in any desirable manner, being preferably 70 formed with a ring *b*, the outer edge of which encircles the ring *a*, and with a rearwardly-extending end *b'*, which is formed with a recess or groove *b²*, having shoulders *b³*, adapted to bear against opposite sides of the handle 75 A. A screw or clamp *B⁴* securely draws together the handle A and the projection *b'* of the plate B, and screws *b⁴*, movable in the peripheral edge of the hub *b*, secure together the rings *b* and *a*. These rings *a* and *b* are 80 so arranged in relation to each other that, as best seen at Fig. 2, the annular guide-groove C intervenes between the adjacent faces of said parts.

D represents a disk revoluble within the 85 groove C and provided with an outwardly-extending disk-shaped projection *D'*, which is formed with a guideway *d*, having the projecting shoulder *d'*.

For the purpose of cheapening the production the disk *D* and its disk-shaped projection *D'* are formed separate one from the other and are firmly secured together by screws *D²*.

Movable within the groove *d* and projecting outwardly therefrom are the wrench-jaws *E*, which are formed in their side faces with recesses *e*, adapted to receive the projecting shoulder *d'* and retain said jaw firmly in position.

The jaws *E* are adjustable toward and away from each other by a suitable adjuster *F*,

here illustrated as a screw having its opposite extremities formed with oppositely-turned threads and its central portion provided with a hand-engaging wheel *f*, which extends through the disk *D* in order that it may be readily engaged from the rear of the wrench through the opening in the ring *a*. The jaws can thus be easily adjusted from the rear of wrench, and when in position are firm and do not have the slightest tendency to yield or spring.

Formed in the disk *D*, and preferably in its edge, are notches *g*, with which are engaged one or more ratchet-dogs *G*, which, as best seen at Figs. 2 and 3, are mounted in recesses *g'* in the projections *b'* of the ring *B*. The rear extremity of the dog *g* is of less diameter than the forward engaging portion, and encircling the same, with one end bearing against a shoulder *g''* of the recess, is a spring *g'''*, which automatically forces said dog outward into engagement with the notches *g* in the disk. The rearward extremity *g'* of the dog *G* extends outwardly beyond the rear face *b''* of the projection *b'* and is provided with a shoulder *g''*, adapted to be engaged by a cam *H* for forcing the dog out of operative engagement with the disk. As preferably constructed, there are two of these dogs side by side, and the cam *H* is provided at its opposite extremities with ways *h* for permitting the opposite cam-faces *h'* to slide beneath the respective projecting ends *g'* when the central portion *h''* of the sliding block carrying said cam-faces is forced in either direction.

The ratchet-dogs *G* are provided with shoulders *g''*, which may be engaged and the dogs rocked a quarter-way around for presenting square shoulders to the like square shoulders formed at the front and rear of each recess in the disk *D*, and thus firmly locking the same to the handle irrespective of the direction in which said handle is moved.

It will thus be seen that by manipulating the block *H* the wrench may be used as a ratchet-wrench and the handle moved in either direction and that by slightly turning the shoulders *g''* the wrench may then be moved as an ordinary one and the handle moved in either direction.

The operation of my invention will be readily perceived from the foregoing description and upon reference to the drawings, and it is evident that the respective parts are cheaply and economically produced, readily assembled, and are efficient in operation.

The detail construction and arrangement of the parts of my wrench may be somewhat varied from that shown and described. Hence I do not limit myself to the precise form and construction.

Having thus fully described my invention, what I claim as new, and desire to secure by Letters Patent, is—

1. In a wrench, the combination of a handle having an annular guideway, a disk revolvable within said guide, adjustable jaws on

said disk, and a ratchet-dog secured to said handle for engaging notches in said disk, substantially as and for the purpose specified. 70

2. In a wrench, the combination of a handle having a hub at one extremity, an annular guide-groove in said hub between the top and bottom faces thereof, a disk mounted in the hub and provided with a flange revolvable 75 within said annular groove, adjustable jaws on said disk, and a ratchet-dog secured to said handle for engaging notches in said disk, substantially as and for the purpose described. 80

3. In a wrench, the combination of a handle having an annular guide-groove, a disk revolvable within said guide, a guideway extending transversely of the disk and formed with a projecting shoulder, jaws mounted in said 85 guideway and formed with recesses in their sides for receiving said shoulder, a screw for adjusting said jaws toward and away from each other, and a dog for locking said disk to the handle, substantially as and for the purpose set forth. 90

4. In a wrench, the combination of a handle having an annular guide-groove, a disk revolvable within said guide, a guideway extending transversely of the disk and formed with a projecting shoulder, jaws mounted in said guideway and formed with recesses in their sides for receiving said shoulder, a screw for adjusting said jaws toward and away from each other, a dog for locking said disk to the handle, and a movable cam or shoulder for disengaging the dog from said disk, substantially as described. 95

5. In a wrench, the combination of a handle having an annular guide-groove, a disk revolvable within said guide, a guideway extending transversely of the disk and formed with a projecting shoulder, jaws mounted in said guideway and formed with recesses in their sides for receiving said shoulder, a screw for adjusting said jaws toward and away from each other, a pair of movable dogs adapted to engage said disk, and a cam or shoulder for engaging said dogs and moving them out of engagement with the disk, substantially as 115 specified. 105

6. In combination, a handle, a disk revolvable within one extremity of said handle, a pair of dogs movably mounted on said disk, notches in said disk provided with a forward and backward engaging-shoulder, a spring-actuated ratchet-dog adapted to engage the notches in the disk, and a shoulder on said dog, whereby the same is engaged and partially rotated for securely locking the disk 120 and handle together when the handle is rotated in either direction, substantially as described. 125

7. In combination, a handle, a disk revolvable within one extremity of said handle, a pair of ratchet-dogs adapted to engage the notches in the disk, a double cam for alternately engaging said dogs, and a shoulder on one or both of said dogs, whereby the same 130

may be engaged and partially rotated for securely locking the disk and handle together when the handle is rotated in either direction, substantially as set forth.

5 8. In combination, a hub having a circular recess, a disk revoluble within said recess, a handle having a ring encircling said disk, clamps for securing the former hub and the handle-ring together, a guideway formed in
10 the disk, jaws mounted in the guideway, and a screw for adjusting said jaws toward and away from each other, substantially as and for the purpose described.

9. In combination, a hub having a circular
15 recess, a disk revoluble within said recess, a handle having a ring encircling said disk, clamps for securing the former hub and the handle-ring together, a guideway formed in

the disk, jaws mounted in the guideway, a screw for adjusting said jaws toward and 20 away from each other, a pair of dogs movable in the hub for alternately locking the dog-carrying disk thereto, and a moving block having camways at its opposite extremities, adapted to engage shoulders on said dogs for 25 alternately throwing them into position, substantially as described.

In testimony whereof I have hereunto signed my name, in the presence of two attesting witnesses, at Honeoye Falls, in the county of 30 Monroe, in the State of New York, this 30th day of April, 1891.

SOLOMON EUGENE HALL.
